CLAIM

The ornamental design for a substrate for spectroscopic analysis, as shown and described.

DESCRIPTION

1. Substrate for spectroscopic analysis

1.1 : Perspective

1.2 : Front

1.3 : Back

1.4 : Top

1.5 : Bottom

1.6 : Left

1.7 : Right

1.8 is a sectional view taken along the vertical center of 1.2; 1.9 is a sectional view taken along the vertical upper portion of 1.2;

1.10 : Perspective view without the cover part

1.11 : Reference view showing the state in use

In the reproductions, the broken lines are for the purpose of illustrating environment only and form no part of the claimed design. The dot-dash broken lines are for the purpose of showing the boundaries of the claim and form no part of the claimed design.
